ROLL PAPER PRINTER

James L. Carver, Birmingham, Ala.

Application September 17, 1949, Serial No. 5,049

Term of patent 14 years

(Cl. D64—11)

To all whom it may concern:

Be it known that I, James L. Carver, a citizen of the United States residing at Birmingham, State of Alabama, have invented a new, original, and ornamental Design for a Roll Paper Printer, of which the following is a specification, reference being had to the accompanying drawing, forming a part hereof.

Fig. 1 is a perspective view of a roll paper printer showing my new design;

Fig. 2 is a plan view thereof; and,

Fig. 3 is an end elevational view of the same.

The essential features of my design are shown in full lines, the broken line showing being for illustrative purposes only.

I claim:

The ornamental design for a roll paper printer, substantially as shown and described.

JAMES L. CARVER.
